(57) **CLAIM**

The ornamental design for protective cycling bib, as shown and described.

DESCRIPTION

FIG. 1 is a front perspective view of the outside of the protective cycling bib of the present invention;

FIG. 2 is a rear perspective view of the outside of the protective cycling bib of the present invention;

FIG. 3 is front view of the outside of the protective cycling bib of the present invention;

FIG. 4 is a rear view of the outside of the protective cycling bib of the present invention;

FIG. 5 is a right side view of the outside of the protective cycling bib of the present invention;

FIG. 6 is a left side view of the outside of the protective cycling bib of the present invention;

FIG. 7 is a top view of the outside of the protective cycling bib of the present invention;

FIG. 8 is a bottom view of the outside of the protective cycling bib of the present invention;

FIG. 9 is a front perspective view of the inside of the protective cycling bib of the present invention;

FIG. 10 is a front view of the inside of the protective cycling bib of the present invention;

FIG. 11 is a rear view of the inside of the protective cycling bib of the present invention;

FIG. 12 is a right side view of the inside of the protective cycling bib of the present invention;

FIG. 13 is a left side view of the inside of the protective cycling bib of the present invention;

FIG. 14 is a top view of the inside of the protective cycling bib of the present invention; and,

FIG. 15 is a bottom view of the inside of the protective cycling bib of the present invention.

The broken lines in the drawings depict stitching and form no part of the claimed design.

1 Claim, 11 Drawing Sheets
